(57) **CLAIM**

The ornamental design for a mounting plate, as shown.

DESCRIPTION

FIG. 1 is a front perspective view of a mounting plate showing our new design.

FIG. 2 is back perspective view of the mounting plate of FIG. 1.

FIG. 3 is a front elevation view of the mounting plate of FIG. 1.

FIG. 4 is a back elevation view of the mounting plate of FIG. 1.

FIG. 5 is a right elevation view of the mounting plate of FIG. 1.

FIG. 6 is a left elevation view of the mounting plate of FIG. 1.

FIG. 7 is a top plan view of the mounting plate of FIG. 1; and,

FIG. 8 is a bottom plan view of the mounting plate of FIG. 1.

The broken lines depict portions of the mounting plate that form no part of the claimed design.

1 Claim, 5 Drawing Sheets
